UNITED STATES PATENT OFFICE.

McLEOD W. THOMSON, OF ALTOONA, PENNSYLVANIA, ASSIGNOR OF ONE-HALF TO ANDREW MORRISON, OF PITTSBURG, PENNSYLVANIA; WILLIAM PATON THOMSON AND SAMUEL GARVER THOMSON EXECUTORS OF SAID McLEOD W. THOMSON, DECEASED.

INSULATED RAIL-JOINT.

No. 813,840.

Specification of Letters Patent.

Patented Feb. 27, 1906.

Application filed April 10, 1902. Serial No. 102,265.

To all whom it may concern:

Be it known that I, McLEOD W. THOMSON, of Altoona, in the county of Blair and State of Pennsylvania, have invented a new and useful Insulated Rail-Joint, of which the following is a full, clear, and exact description, reference being had to the accompanying drawings, forming part of this specification, in which—

- 10 Figure 1 is a top plan view showing the preferred form of my improved joint. Fig. 2 is a cross-section of the same on the line II—II of Fig. 1. Fig. 3 is a top plan view showing another form of the invention. Fig. 4 is a cross-section on the line III—III of Fig. 3. Fig. 5 is a top plan view showing a portion of my invention applied to a fully-insulated joint. Fig. 6 is a side elevation of the form of Fig. 5, and Fig. 7 is a longitudinal section 20 of a portion of one form of my joint on the line VII—VII of Fig. 4.

My invention relates to the class of insulated rail-joints, and is designed to reduce the area of the insulated surface, thereby reducing the liability of injury to the insulation; and also lowering the cost, also to provide a stronger girder-support for the joint than was hitherto possible; further, to arrange the joint to resist expansion and contraction of the rails which tends to injure the separating-blocks between the rail ends, and also to cheapen and improve the joint.

In the drawings, referring to Figs. 1 and 2, 2 represents the heads of the meeting rails, 3 the web, and 4 the base-flanges. I have shown the splice-bars 5 as of the improved form set forth in my United States Patent No. 549,945, dated November 19, 1895, being provided with inwardly-inclined lower flanges 6, extending, preferably, at an angle of about forty-five degrees; but in my broader claims I do not limit my invention to this particular type of splice-bars, the broader features of the invention being applicable to any rail-joint. In this form each splice-bar is planed or otherwise recessed throughout one-half of its length along its upper bearing-face 7 or its lower bearing-surface 8, or both, to allow for the insertion of the strip of insulating fiber 9. The recessed or planed-away portion of each splice-bar is arranged on the opposite side of the joint to that of the other

splice-bar, and the usual separating fiber block 10 is used between the meeting ends of the rails. In the insulated portion of each splice-bar each bolt 11 is insulated from the bar by means of an insulating-fiber collar 12, surrounding the bolt within the bolt-hole in the splice-bar, and by a fiber washer 13 between the splice-bar and the nut or head of the bolt on this side of the rail. In this form of the invention the fiber collars and washers are arranged on the opposite side of one rail to that of the other meeting rail, and as one-half of each splice-bar is thus insulated from the rail and the connecting-bolts no current can pass from one rail to the next. In order to prevent expansion and contraction of the rails from compressing and injuring the separating-blocks between their meeting ends, I preferably employ metal thimbles 14, which surround the central portions of the bolts and fill the annular space between them and the holes through the webs of the rails. The ends of these thimbles are preferably peened over to hold them in place, as shown. I thus make a positive joint in which there is no lost motion and no substantial yielding, since the thimbles driven in around the bolts sustain the pressure resulting from expansion and contraction, thus taking this pressure away from the separating insulating-block. Instead of using the fiber collars between the bolts and the splice-bars I may use fiber collars between the bolts and the rail only, though I prefer the form shown, as it prevents injury to the separating fiber block between the rail ends. In this form also I show an additional support for the joint consisting of a triangular wooden block 15, whose lower faces fit upon the flat inclined inner faces of the splice-bar flanges, this block having a recess under the end of one of the rails, which receives a metal plate 16 with a fiber layer 17 between it and the block to prevent leakage of the current in case the wooden block becomes water-soaked. I have shown the plate as secured by screws to the wooden block. The block is forced against the base of the rails by bolts or other fastenings 18, which extend through the flanges 6 and through the wooden block with suitable interposed washers 19. By drawing up these bolts the flanges are drawn slightly toward

each other and the block forced upwardly to form a firm yet resilient support for the rail ends.

In the form of Figs. 3 and 4 I show the cut-away portions for the half of each splice-bar as arranged opposite to each other on the opposite sides of the same rail. In this form the fiber collars 12' and the washers 13' are arranged at both ends of the bolts 11' on

10 the insulated side of the joint, and the insulating layers 9, with these fiber washers and collars, completely insulate the one rail from both splice-bars; thus preventing passage of the current as before. In other respects the joint is similar to that of Figs. 1 and 2.

15 In the form of Figs. 5 and 6 I show the splice-bars as cut away or recessed throughout their entire length, as in the usual manner, with the wooden block 15' and the se-

20 curing-bolts extending through it and the inclined flanges, and the metal plate and insulating layer between it and one of the rail ends, as in the form of Figs. 3 and 4. In this form the fiber collars 12" and washers 13" are used upon both ends of each bolt, and the

25 metal thimbles 14" are employed between the bolts and the rail-webs, as in the form of the previous figures.

30 The advantages of my invention result from the large reduction in the amount of insulating-surface, which reduces the liability to injury to the insulation; also, from the positive joint, which prevents expansion and contraction of the rails from squeezing and in-
35 juring the separating-block between their meeting ends; also, from the added strength of the joint resulting from the fact that each of the splice-bars is cut away for only one-half its length, thus allowing one-half of
40 each bar to directly contact with and support the rails, and, further, from the improved support for the joint in connection with the inwardly-inclined lower flanges of the splice-bars.

45 Many changes may be made in the form and arrangement of the splice-bars, the insulating layers, and connections without departing from my invention.

I claim—

50 1. An insulated rail-joint having opposite splice-bars, the halves of said bars on the same side of said joint being respectively insulated and uninsulated; substantially as described.

55 2. An insulated rail-joint having opposite splice-bars, the inner faces on one side of the joint being insulated and the corresponding faces on the other side of the joint being uninsulated; substantially as described.

60 3. An insulated rail-joint having opposite splice-bars, the portion of said bars on the same side of the joint being planed or recessed to admit of insulating material; sub-stantially as described.

65 4. An insulated rail-joint having splice-

bars provided with depending flexible flanges inclined inwardly at about forty-five degrees, and having flat inner faces, a triangular block of resilient material below the rail-bases and within the flanges, and cross-bolts 70 or fastenings below the middle of the block and arranged to draw the flanges toward each other to force the block upwardly; substantially as described.

5. An insulated rail-joint having splice-bars with depending flanges inwardly inclined, a wooden block below the rail-bases and between the depending flanges, and cross-bolts or fastenings arranged to draw the flanges toward each other and force the block 80 upwardly; substantially as described.

6. An insulated rail-joint having splice-bars with depending flanges inwardly inclined, a wooden block below the rail-bases and between the depending flanges, a metal 85 plate seated on the block under the end portion of one rail only, and cross-bolts or fastenings arranged to draw the depending flanges toward each other and force the block upwardly; substantially as described. 90

7. An insulated rail-joint having splice-bars with depending flanges inwardly inclined, a triangular wooden block below the rail-bases and between the flanges, a metal plate seated in a recess in the block, and 95 cross-bolts or fastenings arranged to draw the depending flanges toward each other, substantially as described.

8. An insulated rail-joint having splice-bars with depending inwardly-inclined flanges, a wooden block below the end portions of both rails and within the flanges, and a layer of insulating material between the wooden block and the rail-base; substantially as described. 100

9. An insulated rail-joint having splice-bars with depending inwardly-inclined flanges, a triangular wooden block below the rail-bases and between the flanges, a layer of insulating material upon the wooden block, 110 and a metal plate in the recess of the block under the end portion of one rail only; substantially as described.

10. In an insulated rail-joint, an insulating-support extending below the rail ends, 115 insulation thereon, a metallic protecting-plate between the same and the base of at least one of the rails, and insulating means for maintaining the rails in alinement; substantially as described.

11. In an insulated rail-joint, a resilient, insulating-support extending below the ends of the rails and having thereon a metallic plate below the base of at least one rail, insulation between said plate and the support, 125 and insulating means for maintaining the rails in alinement and electrically separating their ends; substantially as described.

12. An insulated rail-joint having inclined depending flanges, a triangular block be- 130

tween said flanges, and bolts or other fastening means arranged to pass through said block and flanges to draw said flanges toward each other and force the block against the base of the rail; substantially as described.

13. An insulated rail-joint provided with inwardly-depending flanges having straight inner faces inclosing with the base of the rail a triangular space, a wooden block in said space having a metal plate secured to the

top face thereof, and bolts or other fastening means securing said flanges together and holding said block against the rail; substantially as described.

In testimony whereof I have hereunto set my hand.

MCLEOD W. THOMSON.
